COMBINED LIQUID AND CUP DISPENSER

Rodney J. Brott, 1340 Yale Ave. NW,
Canton, Ohio 44703

Filed Jan. 21, 1970, Ser. No. 21,019

Term of patent 14 years

Int. Cl. D6—01

U.S. Cl. D33—26

FIG. 3

FIG. 1

FIG. 2

FIG. 4

FIG. 1 is a front elevational view of a combined liquid and cup dispenser embodying my new design.

FIG. 2 is a side elevational view thereof.

FIG. 3 is a top plan view thereof.

FIG. 4 is a bottom plan view thereof.

I claim:

The ornamental design for a combined liquid and cup dispenser, as shown.
